CLAIM

The ornamental design for the ceiling or wall-mounted TV monitor support, as shown and described.

DESCRIPTION

FIG. 1 is a bottom, front, and right side perspective view of a ceiling or wall-mounted TV monitor support showing my new design;

FIG. 2 is a front elevational view thereof;

FIG. 3 is a bottom plan view thereof;

FIG. 4 is a rear elevational view thereof; and,

FIG. 5 is a right side elevational view thereof, the left side being a mirror image of that shown.

FIG.1

FIG.2

FIG.3

FIG.4

FIG.5
